UNITED STATES PATENT OFFICE

2,049,420

GUN CARRIAGE

Gladeon M. Barnes, United States Army,
Hastings, Mich.

Application August 5, 1933, Serial No. 683,755

8 Claims. (Cl. 89—40)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to a gun carriage and is an improvement on the carriage shown in my Patent No. 1,951,338 of March 20, 1934.

In the application there is shown a gun carriage which may be employed with equal facility 10 against both ground and aerial targets. The improvements of this invention are directed to the provision of a novel elevating and depressing mechanism, the gearing of which is carried in the axle unit. The mechanism is arranged to lower 15 the gun mount to the ground, after which operation it may be disconnected from the axle unit. The gun mount may also be easily and quickly coupled to the axle unit and raised to the traveling position.

20 A further object of the invention is to provide a simple and effective means for inoperating the spring suspension of the gun carriage.

To these and other ends, the invention consists in the construction, arrangement and combination of elements described hereinafter and pointed out in the claims forming a part of this specification.

A practical embodiment of the invention is illustrated in the accompanying drawings, 30 wherein:

Fig. 1 is a view in side elevation of the gun carriage showing the pedestal in the raised position.

Fig. 2 is a similar view showing the pedestal in 35 the lowered position.

Fig. 3 is a plan view of the pedestal showing the manner of applying outriggers.

Fig. 4 is a view in front elevation, parts being 40 in section of the axle housing and taken generally on the line 4—4 of Fig. 5.

Fig. 5 is a sectional view on the line 5—5 of Fig. 6.

Figs. 6 and 7 are sectional views on the respective lines of Fig. 5.

45 Fig. 8 is a fragmentary plan view of the axle housing, parts being broken away.

Fig. 9 is a sectional view on the line 9—9 of Fig. 5.

Fig. 10 is a sectional view through the spring 50 inoperating means.

Fig. 11 is a sectional view on the line 11—11 of Fig. 8.

Fig. 12 is a plan view of the pedestal and wheeled axle unit and

55 Fig. 13 is a view in elevation of the slide.

Referring to the drawings by characters of reference:

There is shown a gun carriage consisting generally of a pedestal mount A, supported by a detachable wheeled axle unit B and by split trail members C, and supporting a top carriage D of typical anti-aircraft design in which a gun E is trunnioned as at F adjacent the breech to provide for high angle firing.

The wheel unit comprises an axle 5 equipped with pneumatic-tired wheels 6. A transverse semi-elliptic leaf spring 7 shackled to upstanding arms 8 (Fig. 4) at each end of the axle is centrally clipped as at 9 (Fig. 11) to an axle housing 10. The housing is held against rotational movement with respect to the axle by means of conventional rubbing blocks 11 fixed to the axle and having sliding engagement with the front and rear vertical walls of the housing.

Secured to the rear wall of the axle housing 10 (Fig. 5) are spaced, vertically extending guides 12—12 for mounting channeled side-bars 13—13 integral with a slide 14 which is in the form of a wide plate. Each side bar is provided on its outer side with a rack 15. As seen in Figs. 8 and 25 11 the slide 14 may be locked against movement relative to the axle housing 10 by means of a pair of bolts 16—16 carried by the axle housing and normally urged by springs 17 into apertures 18—18 in the slide. One convenient manner of operating the bolts consists in providing a common rod 19 having levers 20—20 on its opposite ends for engaging the bolts. In the illustration given the levers 20 are each in engagement with a pin 21 on the bolts.

30 Rotation of the rod by means of a handle 22 reciprocates the bolts 16—16 simultaneously and causes them either to enter or be withdrawn from the apertures 18 in the slide 14.

As shown in Fig. 7 the slide includes a horizontally disposed rib or shelf 23 adjacent its upper end and adapted to hook under the top plate 24 of the pedestal. The slide 14 is also adapted to rest on the bottom plate 25 of the pedestal. The slide is clamped to the pedestal in a manner similar to that disclosed in my copending application, Serial No. 480,670, filed September 9, 1930, and accordingly this mechanism will be but briefly described.

Each of the side bars 13 (Fig. 12) of the slide 50 14 carries a latch 26 engageable in a notch 27 formed in spaced webs 28—28 on the pedestal. A cam lever 29 fulcrumed on a pin 30 in front of the notch serves to lock the latch in place.

In order that the pedestal A may be raised and 55

lowered relative to the wheeled axle unit B a system of gearing is carried by and arranged within a casing 31 on the axle housing 10 and is adapted to actuate the racks 15. Referring to Figs. 4 and 5 a pair of operating crank handles 32 and 33 are mounted in the front wall of the casing 31 and carrying pinions respectively 34 and 35 meshing with opposite sides of a gear wheel 36. The gear wheel 36 includes a pinion 36a which on one side 10 drives a train of gearing comprising twin gear wheels 37-38-39, and pinions 40 and 41, the latter meshing with the rack 15 on the corresponding side of the slide 14. On the opposite side of the gear wheel 36 its pinion 36a drives a train of gearing including a reversing gear 42 twin gear wheels 43-44 and 45 and pinions 46 and 47. The latter meshing with the rack 15 on its side of the axle unit.

The gears 39, 40 and 41 and 45, 46, 47 are positioned on the rear side of the axle housing and are housed respectively in casings 48 and 49.

Since the drive to the pinions 41 and 47 is taken from the common gear wheel 36 irrespective of which of the crank handles 32 or 33 is operated, the pinions will be moved in unison equal amounts and thereby prevent any tendency to bind on the part of the axle housing and slide during their relative movement. The ratio of the gearing is such that the slide and pedestal A can 30 easily be raised by operating only one of the crank handles.

As shown in Fig. 12 the pedestal A may additionally carry a raising and lowering mechanism in the manner disclosed in Patent No. 1,801,423 of April 21, 1931. The mechanism consists of a 35 pair of jacks 50-50 operated by pinions 51-51 on a common shaft 52. The main purpose in providing this auxiliary mechanism is to afford an additional firing position as will be described hereinafter.

Referring to Figs. 10 and 11 there is shown a simple and convenient mechanism for incapacitating the spring suspension when it is desired to fire the gun from a position wherein the wheels 6 are in direct engagement with the ground and 45 constitute a support for the front part of the gun carriage. A pair of bolts 53-53 secured to the under side of the axle 5 each projects through an aperture 54 in the bottom plate 55 of the axle housing. On each bolt is a nut consisting of an 50 enlarged head 56 constituting a hand wheel, a collar 57 adapted to bear against the under side of the bottom plate, and a sleeve 58 of reduced external diameter adapted to pass through the aperture 54 and bear against the under side of 55 the axle 5.

When the nut is screwed on the bolt until the collar and sleeve bear respectively against the axle housing and the axle (Fig. 10), the housing and axle will be securely locked against relative 60 movement. Consequently when the gun is fired the shock of discharge will pass from the axle housing to the axle and thence through the wheels into the ground. Upon unscrewing the nuts the load of the axle housing will be supported by the spring 7.

In the travelling position (Fig. 1) the mount A is supported by the slide 14 and is securely held thereto by the latches 26 which are locked by the cam levers 29. The slide 14 is locked to the axle housing by means of the bolts 16.

When it is desired to lower the pedestal A to the ground (Fig. 2) the bolts 16 are retracted to free the slide 14. The slide and the pedestal to which it is attached may be allowed to drop freely or 75 the lowering may be controlled by acting on the

crank handles 32 and 33. By releasing the latches 26 the wheeled axle unit B can be moved away from the pedestal. This procedure is reversed when the pedestal is to be raised from the ground and placed in the travelling position. 5

By virtue of the structure provided in the improved gun carriage, four firing positions may be obtained.

First firing position.—The trails C are opened about 100 degrees and their spades driven into the ground. The spring suspension 7 is inoperated by acting on the nuts 56-57-58. The gun may now be fired up to 80 degrees in elevation and through 100 degrees in traverse.

Second firing position.—The pedestal A is lowered to the ground as in Fig. 2, the trails C being opened and resting on the ground. The movement in elevation and traverse is the same as in the first firing position but increased stability is obtained because of the reduced height of the 20 trunnion above the ground. The stability may be increased by raising the axle unit so that its wheels are off of the ground and the weight of the axle unit is added to the carriage.

Third firing position.—After lowering the 25 pedestal to the ground, the wheeled axle unit is removed and two outriggers 59-59 are attached to the pedestal opposite the trail members C. The gun can be fired through 360 degrees 30 traverse.

Fourth firing position.—With the mount in the travelling position the jacks 50 are actuated to lower their float to the ground. Further actuation of the jacks raises the pedestal A and the wheeled axle unit B until the latter is clear of the 35 ground. With the trails C opened and emplaced the gun may be fired up to 80 degrees in elevation and through 100 degrees of traverse. The pedestal may also be lowered to the ground after uncoupling it from the wheeled axle unit. 40

I claim:

1. In a gun carriage, a mobile unit including an axle, a leaf spring overlying the axle and secured thereto, an axle housing suspended by the spring, a plate slidably mounted on the rear side of the housing, means for locking the plate to the housing, racks on the sides of the plates, pinions mounted in the housing in rear of the axle and meshing with the racks, a gear wheel mounted in the housing in front of the axle, a train of gearing leading from each of said pinions to the gear wheel, one of said trains additionally including a reversing gear wheel, driving pinions meshing with opposite sides of said gear wheel, a crank handle for each of the driving pinions, and a gun mount removably attached to the plate for support thereby.

2. In a gun carriage, a mobile unit including an axle, a spring-suspended axle housing, a plate slidably mounted on the rear side of the housing, 60 means for locking the plate to the housing, racks on the sides of the plates, pinions mounted in the housing in rear of the axle and meshing with the racks, a gear wheel mounted in the housing in front of the axle, a train of gearing leading from each of said pinions to the gear wheel, one of said trains additionally including a reversing gear wheel, driving pinions meshing with opposite sides of said gear wheel, a crank handle for each of the driving pinions, and a gun mount removably attached to the plate for support thereby.

3. In a gun carriage, a mobile unit including an axle, a spring-suspended axle housing, a plate slidably mounted on the rear side of the housing, 75 means for locking the plate to the housing, racks

on the sides of the plate, pinions mounted in the housing and meshing with the racks, a gear wheel mounted in the housing, a train of gearing leading from each of said pinions to the gear wheel, one of said trains additionally including a reversing gear wheel, driving pinions meshing with opposite sides of said gear wheel, a crank handle for each of the driving pinions, and a gun mount removably attached to the plate for support thereby.

5. In a gun carriage, a mobile unit including an axle, a spring-suspended axle housing, a slide carried by the housing at one side of the axle, means for locking the slide to the housing, racks 15 on the sides of the slide, pinions mounted in the housing on parallel axes and meshing with the racks, actuating mechanism for driving said pinions including a common member, a dual control for said common member, a gun pedestal adapted to be carried by the mobile unit and to be em- 20 placed on the ground, and a quick-detachable connecting means between the slide and pedestal.

6. In a gun carriage, a mobile unit including an axle, a spring-suspended axle housing, a slide carried by the housing at one side of the axle, means for locking the slide to the housing, racks 25 on the sides of the slide, pinions mounted in the housing on parallel axes and meshing with the racks, means for actuating the pinions in unison, 30 a gun pedestal adapted to be carried by the mo-

bile unit and to be emplaced on the ground, and a quick-detachable connecting means between the slide and pedestal.

6. In a gun carriage, a mobile unit including an axle, a spring-suspended axle housing, a slide carried by the housing at one side of the axle, means for locking the slide to the housing, means carried by the housing for raising and lowering the slide, a gun pedestal adapted to be carried by the mobile unit and to be emplaced on the 10 ground, and a quick-detachable connecting means between the slide and pedestal. 5

7. In a gun carriage, a mobile unit including an axle, an axle housing having a bottom plate provided with apertures, a spring suspension be- 15 tween the axle and axle housing, bolts secured to the under side of the axle and projecting through the apertures in the axle housing, a nut on each bolt having a sleeve adapted to pass through an aperture in the axle housing and bear against 20 the axle and also having a collar adapted to bear against the axle housing.

8. In a gun carriage, a mobile unit including an axle, an axle housing resiliently suspended by the axle, bolts secured to the axle, a nut on each bolt 25 having an inner end adapted to bear against the axle and having an outer portion adapted to bear against the axle housing.

GLADEON M. BARNES.
